* cited by examiner

Primary Examiner — Brian N Vinson(74) Attorney, Agent, or Firm — Leanne Taveggia Farrell; Westman, Champlin & Koehler, P.A.(57) CLAIM

The ornamental design for a lamp, as shown and described.

DESCRIPTION

FIG. 1 is perspective views of a lamp showing our new design; FIG. 2 is a front view thereof; FIG. 3 is a back view thereof; FIG. 4 is a left side view thereof, the opposing right side view being a mirror image; FIG. 5 is a top view thereof; and, FIG. 6 is a bottom view thereof.

The broken lines shown in the drawings are included for purposes of illustrating portions of the lamp and form no part of the claimed design.
